UNITED STATES PATENT OFFICE.

HERMAN HAUPTMAN, OF PITTSBURGH, PENNSYLVANIA.

PENCIL ATTACHMENT FOR SECTIONAL RULES.

1,227,614.

Specification of Letters Patent. Patented May 29, 1917.

Application filed September 30, 1916. Serial No. 123,036.

To all whom it may concern:

Be it known that I, HERMAN HAUPTMAN, a subject of the Emperor of Austria, residing at Pittsburgh, county of Allegheny, and 5 State of Pennsylvania, have invented certain new and useful Improvements in Pencil Attachments for Sectional Rules, of which the following is a specification.

This invention relates to a pencil attachment for sectional rules, and has for its 10 object to provide means secured to one of the sections of the rule for connecting a pencil therewith, said means not impairing in any manner the extending or the folding 15 of the rule.

Further objects of the invention are to provide a pencil attachment for rules which is simple in its construction and arrangement, strong, durable, efficient and convenient in its use, and inexpensive to manufacture.

With the foregoing and other objects in view the invention consists of the novel construction, combination and arrangement of 20 parts as hereinafter more specifically described and illustrated in the accompanying drawing, wherein is shown an embodiment of the invention, but it is to be understood that changes, variations and modifications 25 can be resorted to which come within the scope of the claim hereunto appended.

In the drawings wherein like reference characters denote corresponding parts throughout the several views:—

35 Figure 1 is an elevation of a sectional rule showing the adaptation therewith of a pencil attachment in accordance with this invention and further showing the attachment secured to two of the sections of the 40 rule.

Fig. 2 is a plan of the blank from which the attachment is formed.

Referring to Figs. 1 and 2 of the drawings 45 1, 2, 3 and 4 denote the sections of a rule and connected to each of the sections 1 and 4, which are the outer sections of the rule, is a pencil attachment in accordance with this invention. Each of the sections 1 and 4 is provided with two pairs of longitudinally extending spaced slots and the slots of one pair are indicated at 5 and the slots of the other pair at 6.

The blank from which the pencil attachment is formed consists of a longitudinally

extending body 7, formed of a narrow strip 55 of metal, and which has projecting laterally, at points intermediate the ends thereof, two pairs of bendable wings, the wings of one pair are indicated at 8 and the wings of the other pair are indicated at 9. 60

Formed integral with the body 7, and spaced from the wings 8 and 9, are two pairs of bendable projections, and the projections of one pair are indicated at 10 and the projections of the other pair at 11. The 65 wings 8, 9 are bent outwardly and curved to provide clamps, the clamps formed by the wings 8 are indicated at 12, and the clamps formed by the wings 9 are indicated at 13. The projections 10 and 11 are bent 70 inwardly to provide securing members and the members formed by the projections 10 are indicated at 14 and those formed by the projections 11 are indicated at 15.

When the attachment is connected with 75 the section of a rule, the projections 10, 11 are passed through the slots 5, 6, of the rule section and then bent upon the inner face of the rule section whereby the attachment is detachably connected with the section, 80 as illustrated in Fig. 1.

The body 7 of the attachment is such as not to interfere with the graduations of the rule sections and the material from which the attachment is made is so thin as 85 not to interfere to any great extent with the rule sections when one or more sections are connected to the rule.

What I claim is:—

A pencil attachment for rules comprising 90 an elongated flat body portion provided near each end with a pair of oppositely disposed projections capable of being bent outwardly to provide clamping means, said body portion further provided at each end 95 with a pair of laterally projecting oppositely disposed lugs capable of being bent inwardly to extend through a rule for securing said body portion therewith the lugs at the ends of the body portion spaced from 100 the other lugs.

In testimony whereof I affix my signature in the presence of two witnesses.

HERMAN HAUPTMAN.
